SCANNING RADIO RECEIVER

Sidney Y. White, Wilmette, Ill.

Application February 29, 1940, Serial No. 321,378

14. Claims. (Cl. 250—20)

This invention relates to a radio receiver having preferably a selectivity curve of just sufficient band width to pass the type of transmission desired and adapted to explore a portion of the spectrum to locate a carrier wave and to stop exploring when a carrier wave is encountered. This type of receiver is hereinafter referred to as a "scanning" receiver. The invention is in the nature of an improvement on the scanning receiver disclosed and claimed in Serial No. 321,377, filed February 29, 1940, in my name. In said application a radio receiver is disclosed which is especially adapted for the reception of carrier waves having a frequency higher than 20 megacycles and wherein inertialess scanning means are provided for rapidly scanning a portion of the spectrum in which a carrier is expected to occur. Should there be several transmissions operative in that portion of the spectrum the receiver therein disclosed will lock on the first carrier encountered, which may not be the one desired.

Scanning receivers of the ordinary type have been suggested which stop on each carrier consecutively and remain in this condition until a complete series of dots which identify a particular carrier have been received. If this carrier is unwanted, the receiver resumes the scanning condition until it encounters a carrier having the predetermined number of dots which distinguish the desired carrier. Having located such a carrier, the receiver remains receptive to the carrier until either the receiver or the carrier is turned off.

It is easily realized that this is a time-consuming process, and, when a large number of channels must be explored, a transmitter must be transmitting its identifying code for a very considerable time to insure that the receiver has had time to locate it. It is one of the main objects of this invention to avoid this delay by identifying the signal with a "tone" and providing means whereby the receiver locks on a carrier having a predetermined "tone."

This "tone" can be of sub-audio, audio or super-audio frequency. The sub-audio range is rather unattractive due to the long time interval required for one cycle and for filter voltage build-up, as well as the size and weight of the filter. The tone may well be in the audio range, but if it is desired that the tone be on all the time, some complication ensues from the necessity of putting a "hole" in the audio response curve so that the tone would not be heard sufficiently loudly to interfere with the speech transmission.

Receivers of the communication type often have a cut-off of 3000 cycles as the upper limit of the audio band transmitted. The identifying tone frequencies may, therefore, commence at 5 4000 cycles, for example, and continue on up indefinitely, say to 20,000 cycles or even higher. A further use of a receiver of this type would be to locate and properly tune in television signals 10 which would be identified by the "tone" provided by the scanning frequency, which at present is of the order of 40,000 cycles, or by any synchronizing frequency present on the carrier. The term "tone" as hereinafter used in the specification and claims is intended to include all of 15 the above mentioned frequencies.

Obviously this tone can be left on all the time with say 30% modulation, or could only be impressed on the carrier for the purpose of contacting the receiver, which should occur in one 20 or two seconds. In this case the tone would modulate the carrier 100%. Arrangements could also be made so that the tone plus the voice at all times would add up to 100% modulation; that is, at a given period, if the voice energy were zero 25 the tone would be 100% modulation on the carrier, but at another time if the voice energy were 100% the tone energy would be zero. This would be feasible due to the extremely short time intervals during which speech peaks reach 100% 30 modulation, and the receiver can easily be made not to relinquish contact during these extremely small intervals.

The advantage of having the tone on all the time is especially marked in mobile work, where 35 due to interference patterns on the ground or the attitude of a plane in the air, there may be short intervals where zero signal exists in the receiver antenna. After this condition ceases to exist, however, rapid and positive contact with the carrier must once more be obtained, and 40 naturally, if the tone were not there, the receiver would not lock on the carrier.

The preferred way to utilize this tone is to provide a receiver of the type shown in the aforementioned application but in which the director device which serves to effect the locking on the carrier is normally inoperative and is only rendered operative to perform the locking function 45 by a switching device which is responsive to a predetermined tone impressed on the desired carrier.

In a case where the tone is only impressed 50 on the carrier for several seconds and then removed, it is obvious the proper carrier has been located and the tone preferably triggers off a

switch which brings about the lock-on-carrier condition which will then be self-maintaining as long as the carrier wave is received.

It is a feature of the present invention in addition to that described in the aforementioned application, that the sweep voltage is left on continually and is overcome by a much higher voltage generated by a director device which is energized by the carrier.

Each receiver of a group could be arranged to respond to either of two tone frequencies; one of these (for example 5,000 cycles) could be common to all the receivers, and the other (for example 7,000 cycles) could be specific to only one receiver. All receivers in the group would then lock on a carrier modulated with 5,000 cycles and such a carrier would then serve as a general call to all the receivers, while a carrier modulated with 7,000 cycles would act as a specific call to the one receiver only.

In the case of a complete communication system where private channels may be set up between two or more of the units in the group, and it is desired to break up these conversations to give precedence to a general call, it would be necessary to have two receivers at each station, one of which would respond to the general call only, and the other respond to the individual call only. In that case, if one receiver were working on an individual call, a general call would actuate the other receiver at each station, and the latter receiver could be arranged to take over the receiving transducer from the individual channel, thus breaking up the private conversation and forcing everyone to listen to the general call.

It will be realized that once a receiver is designed to respond only to an identifying tone, it must not respond to a carrier it passes over, regardless of its strength, which does not have the exact tone identification for which the receiver has been designed. A feature to be guarded against in the construction of a receiver which rapidly scans a large number of channels is the building up of paralyzing transients which will in effect cast a shadow behind such a strong undesired carrier, so that the receiver will keep on sweeping, but will be paralyzed until the excess voltage charges leak off, as for example from the grid circuits. This means that the desired station may be hidden in such a shadow so that the receiver will lack the necessary sensitivity to pick it up promptly when sweeping in that direction, but when returning in the sweep from the opposite direction will, of course, pick it up satisfactorily.

In high speed scanning receivers of the tone identified type the action of the automatic volume control device should be either extremely fast or extremely slow. If it has some intermediate value, it will cause the receiver to lose sensitivity for a time just after passing over an undesired carrier. Since the receiver continues scanning regardless of the AVC voltage developed, there would be a certain time of AVC voltage decay during which the receiver will be quite insensitive, and unable to pick up a weak desired carrier which might be encountered. In scanning at the rate of several hundred channels per second, a high speed AVC action is rather difficult to secure, and an extremely slow one is preferred which will build up only a negligible voltage in passing through an undesired carrier at these high scanning speeds by choosing large values for C9 and R18.

Requirements of the tone operated switching device, hereinafter referred to as the "tone switch", are severe. We may sweep at the rate of 100 to 200 channels per second, equivalent to 5 passing over the entire broadcast band in considerably less than one second. Differently expressed, it means passing through a desired carrier in substantially 5 to 10 milliseconds. In that time the tone switch must build up to full 10 amplitude of action, must charge up its filter condensers, and energize the director, which in turn must build up and charge its filter condensers, and the signal must be locked on and held, which requires that no transient surges 15 can be allowed to build up, no matter how small, which on discharge would tend to cause release of the carrier once it had been identified and locked on.

The tone can be recognized and utilized by 20 mechanical resonant systems, as for example, by a tuning fork; or by a resonant electrical circuit or several such circuits in cascade. The selectivity must be of such a high order that, if the circuit is tuned, for example, to accept 7000 cycles, no response whatsoever can be tolerated 25 at 6000 cycles or 8000 cycles. It will be realized that the desired signal modulated at 7000 cycles may generate a voltage of one microvolt but an undesired signal modulated at 6000 cycles may 30 generate a voltage of 100,000 microvolts and the receiver must not lock or even hesitate when passing through the 100,000 microvolt undesired signal. The customary manner of securing this selectivity is to use as highly resonant circuits 35 as practical and cascade them until the desired degree of selectivity is attained. The size and weight of such a filter is considerable, and it has the further serious objection that the time interval required for full resonant voltage to 40 build up is too long to permit the receiver to scan at a sufficiently rapid rate. It is one of the main objects of the present invention to provide a selective filter device which is light and compact and which responds sufficiently 45 rapidly as to cause the receiver to lock on the desired carrier. In cases where it is desired that the receiver respond to a master tone that is common to a group of receivers as well as to an individual tone specific to one receiver only, it 50 is a further object of the invention to provide two such filter devices whose rectified outputs are connected in series or in parallel.

Another object of the present invention is to 55 provide a director device for locking the receiver on a desired carrier, and in which no voltage is built up while passing over an undesired carrier. For this purpose the director device is preferably provided with a driver tube which has a screen grid. The screen grid is normally held at substantially -20 volts to absolutely block 60 the plate current until voltage is applied from the tuned filter switch circuit which raises the screen voltage to substantially +100 volts for normal operation of the director.

In the preferred embodiment of the invention, 65 the director device varies the frequency of a local oscillator through the action of a control tube, and it is a further feature of the invention that the director is connected to the control grid of the control tube by a circuit having a large 70 time constant. This circuit serves to filter out noise current components which appear in the director circuit. In the case of weak signals of the order of the noise level, a considerable noise 75 voltage is developed in each branch of the di-

rector device. These branches are carefully matched and balanced and the noise voltages developed tend to cancel out when the signal is properly tuned in. When a considerable amount of director voltage is required to maintain the receiver tuned to the signal, one branch of the director develops more voltage than the other so that the balance is destroyed and a very considerable fluctuating noise voltage appears superimposed on the direct current director voltage so extremely effective noise filtering is required.

When a desired signal is intercepted, it is properly tuned in and the function of the director is then to hold it in. In the next few milliseconds the sweep oscillator continues to generate a voltage of a few millivolts which tends to keep the receiver in a scanning condition. It is then only necessary for the director to generate a few millivolts of opposite polarity to keep the receiver locked on the carrier. As the frequency of the sweep voltage is at a rather slow rate, a very large time constant filter may be used to minimize the noise fluctuation voltages.

For a better understanding of the invention, reference is made to the following description taken in connection with the accompanying drawings in which:

Fig. 1 is a schematic circuit diagram in block form of a radio receiver embodying the invention; and

Fig. 2 is a schematic circuit diagram of the radio receiver of Fig. 1 in which the circuits of several of the component parts are shown diagrammatically in more detail.

Referring to Fig. 1 the receiving system is shown as comprising an antenna 1 connected to the tunable input circuit 2 of a radio frequency amplifier 3, the circuit 2 being permeability tuned over a band of frequencies as indicated at 4. The output circuit of amplifier 3 feeds in turn a first detector or mixing device 5, an intermediate frequency amplifier 6, a second detector 7, audio frequency amplifier 8, band pass filter 9 and a translating device, such as the earphones 10. If desired, the output level of the receiver may be maintained at a substantially constant level by an automatic volume control device 11, which may be of any known type. The amplifier 3, mixing device 5, intermediate frequency amplifier 6, detector 7 and audio amplifier 8 may be of any known type, as used in superheterodyne receivers for the reception of modulated carrier waves. The oscillator frequency is supplied to the mixing device 5 by an oscillator 12, whose frequency is controlled by a control tube 13 which is subject to the control of a sweep oscillator 14 preferably generating a low frequency, such as one half cycle per second. The control tube 13 is also subject to the control of a director device 15 which is in turn controlled by a switch device 16 operated by one of the tone filters 17, 17' which are connected in parallel to the audio frequency amplifier 8.

Referring now to Fig. 2, the audio amplifier 8 is shown as comprising the tubes VT7 and VT9 which are resistance coupled, as shown, the latter tube also being provided with an extra plate 18 which cooperates with the tube cathode 19 to provide a diode rectifier. The output circuit of tube VT9 is connected to the earphones 10 by means of a band pass filter 9. The filter comprises a push pull output transformer 20 which is designed to have a considerable amount of leakage reactance and whose primary winding

has a condenser 21 connected across it. By a proper choice of the value of this condenser, a sharp cut off above 3000 cycles is obtained so that any tone frequency of 4000 cycles or higher ceases to be annoying to the user, even when the tone frequency is left continually on during the speech transmission. It is found that a filter of this type will allow the usual range of telephonic speech frequencies to pass and provide a rapid attenuation above those limits.

The scanning device 14 comprises the vacuum tubes VT5 and VT6, the plate of each tube being connected to the grid of the opposite tube through the condenser C1 and C2 having a capacity of 0.5 mfd., and the grids of the tubes being connected to their cathodes through the 2.0 megohm resistors R5 and R6, to thereby produce a half cycle sweep voltage of substantially square wave form. This voltage is supplied to the control grid of a control tube VT4 through a lead 22, resistor R7 and condenser C3, the latter serving to block off the direct current voltage. Resistor R1 and condenser C4 act as a filter to take voltage of square wave form at the plate of tube VT5 and change it to a substantially sinusoidal wave form. At the same time the resistor R7, being 10 megohms, reduces the voltage from several hundred volts to ± 3 volts. A further advantage in making R7 so large is that it does not destroy the symmetry of the sweep oscillator 14. It will be realized that the half cycle oscillator covers the entire scanning spectrum in one direction completely in one second. A control voltage is also supplied to the control grid of VT4 through resistor R8 and the director line 22 by the director device 15.

The director 15 consists of a director driver tube VT1 whose control grid is connected through lead 23 and condenser 24 to the output of the intermediate frequency amplifier 6, the cathode of the tube being connected to ground through the resistors R14 and R15 connected in series. The tube cathode is connected to the B supply voltage source through the resistor R13 and the B supply is also connected through the resistor R16 to the screen grid 25 of the tube VT1 and also to the plate of the switching tube VT10, as shown. The plate circuit of tube VT1 comprises the low impedance primary windings 26 and 27 which are coupled, respectively, to the secondary transformer windings of the circuits TC1, TC2, one of which is tuned to a frequency of from 5 to 10 kilocycles above the intermediate frequency, and the other of which is tuned by the same amount below the intermediate frequency. These circuits feed the diodes VT2 to develop a differential voltage across the resistors R1 and R2. As shown, one end of the resistor R1 is grounded and one end of resistor R2 is connected by director line 22 to the control grid of tube VT4.

The oscillator is shown as comprising the tube VT3 whose cathode is grounded and whose plate circuit is provided with a tuned tank circuit comprising the coil L1 and condenser 28. It is found that by making the condenser 28 of fixed value and varying the inductance of coil L1 so as to change its permeability, as by means of a powdered ferro-magnetic core, as indicated at 29, substantially equal percentage tuning effects are secured throughout the band of frequencies.

It is found that the ordinary hydrogen reduced iron cores are not at all suitable for permeability tuning at frequencies of the order of 100 megacycles. However, it has been found that

ferromagnetic cores known under the trade name "Aladdinite" are very satisfactory. These cores are made from a synthetically produced ferromagnetic mass powder consisting substantially wholly of magnetic oxide of iron in the form of minute particles, substantially all of which, as they appear under a microscope, are of generally rounded form. These particles are preferably molded into cores by mixing with several per cent of "Bakelite" as a binder.

Considering the circuit which is grounded at the lower end of coil L1, the oscillator grid receives charging current through L2 representing the mutual inductance of the tickler coil with L1. The grid current at the end of L2 is thus exactly 180° out of phase with the circulating current in L1. Before reaching the grid of tube VT3, the current must pass through some series leakage inductance, represented by L3, which produces a reactance of rather small amount, but which is quite effective due to the very heavy current flowing through it. At the grid of VT3, energy is supplied which is so phased in relation to that of the plate tank circuit as to cause the tube to oscillate, but is not quite 180° phase angle from the plate. The amount of phasing may be varied as desired, by making L3 of the proper value, even, if necessary, by winding an additional uncoupled coil in series with the grid, or by more loosely coupling L2, and by making this coil larger we can increase the leakage inductance to any desired amount without having any physical coil, as represented by L3. With this energy, preliminarily phased, as described, the grid energy of tube VT4 may now be further phased in the same direction by the series resistance R8.

For the purpose of controlling the frequency of the oscillations generated by oscillator VT3, the plate of tube VT3 is connected to that of a control tube VT4 and both plates connected to the mixing device 5 through a condenser 30. Control tube VT4 is provided with the usual supply voltage, its inner grid being given a normal bias of approximately -6 volts by connecting its cathode to the bleeder resistor 31 at a point approximately this number of volts above ground. This permits the operation of the tube at the mid-point of its control range, as determined by plotting a curve of grid bias against oscillator frequency which results in an S-shaped curve, so that we secure operation about the mid-point thereof. The voltage generated by the sweep oscillator 14 is arranged to be a total peak-to-peak of 6 volts so that the effective voltage at the grid of control tube VT4 from the sweep oscillator is ± 3 volts. This voltage swing changes the frequency of the oscillator tube VT3 by an amount sufficient to sweep the receiver through a range of frequencies approximately 1% of the carrier frequency. When the director is rendered operative, in a manner to be described, it generates a voltage of ± 20 volts even on the weakest signal for which the system is designed. This voltage is sufficient to overpower the sweep voltage and to tune the receiver to the incoming carrier within approximately 1 kilocycle, at a carrier frequency of 150 megacycles.

The means for rendering the director operative upon the reception of a carrier modulated by the proper tone frequency comprises the switching tube VT10 which is energized by the tone filter 11. This filter comprises an amplifying tube VT8 whose grid is connected to the

audio amplifier through a small condenser C7 and the coupled resonant circuits TC3 and TC4 which may be permeability tuned to the desired tone frequency, as indicated at 32. Where the identifying tone frequency is within the preferred range of from 4000 to 20,000 cycles, each of these circuits is tuned to that frequency.

The selected tone frequency voltage is amplified by tube VT8 in a resistance coupled stage and rectified by the circuit including the diode 18, 19 and resistor R11, one end of which is grounded. The grid of the audio output tube VT9 is normally biased to -10 volts by means of the self-biasing resistor 33 which is shunted by a condenser 34. This arrangement provides a normal negative voltage of -10 volts on the plate 18 of the diode with reference to its cathode 19. A signal must, therefore, develop a potential on the positive peaks in excess of the 10 volts negative bias in order to permit the diode to rectify. A weak desired signal which may, for example, be modulated at a tone frequency of 7000 cycles for purposes of station identification, be scanned by the action of the oscillator 12, control device 13 and sweep oscillator 14, and in about 3 milliseconds builds up in the resonant circuits TC3 and TC4 to approximately full amplitude. This voltage is amplified by tube VT8 and impresses substantially 20 volts positive peak voltage on the diode plate 18, thus overcoming its 10 volts negative bias and producing a rectified output voltage across R11 of the order of 10 volts. This voltage is filtered by the filter circuit comprising resistor R12 and C8 and will be hereafter referred to as the switch operating voltage.

It is assured that no director voltage is developed when the receiver is passing through the extremely strong undesired carrier by maintaining the screen 25 at a potential of from -20 to -30 volts, which is sufficient to absolutely block the tube VT1 so that no director voltage is developed in the circuits TC1, TC2. The screen 25 is connected to the plate of the tube VT10 which, being unbiased, has a very low resistance and draws such a large current through R16 that the screen voltage is about 20 volts above ground. Since the cathode of this tube remains at substantially 50 volts above ground, the screen voltage is 30 volts negative with respect to the cathode.

When a desired signal is encountered and current of the tone frequency builds up the switch operating voltage as before described, this voltage is negative due to the passage of current through the diode 18, 19 and resistor R11. This negative voltage being applied to the grid of tube VT10 is sufficient to block this tube with the result that the flow of current through resistor R16 is considerably decreased and the voltage of screen 25 immediately rises to about 150 volts above ground and VT1 is then operative. The carrier wave of a desired station now being received, resonant voltage are built up in the circuits TC1 and TC2, the differential voltage developed being applied to the grid of the control tube VT4. This voltage is sufficient to override the sweep voltage developed by the sweep oscillator 14 and lock the receiver on the carrier. The noise voltages appearing in the director line 22 are preferably filtered out by the filter circuit which comprises the internal resistance of the director device which is about 2 megohms, and the condenser C4 which has a capacity of 0.5 microfarad.

It is to be noted that both the tone and the carrier must be present to maintain this condi-

tion. If either one disappears for more than a few milliseconds, the director driver tube VT1 becomes blocked so that no director voltage is developed and the receiver instantly resumes the scanning condition under the control of the sweep oscillator 14.

Should a very strong undesired carrier be encountered having, for example, 6000 cycles modulation on it, the requisite switch operating voltage will not be developed by the resonant circuits TC3, TC4.

The voltage developed by the circuits TC3, TC4 as determined from their combined selectivity curves at 6000 cycles is only about one-tenth of that developed at their resonant frequency of 7000 cycles. But this voltage difference in itself would be insufficient to prevent the development of an effective switch operating voltage which might lock the receiver on an undesired carrier which may be 100,000 times stronger. One of the means which has been found effective to prevent the development of the switch operating voltage for an undesired carrier comprises the tube VT7, the constants of this tube and its associated circuits being designed so that the maximum power developed in its plate circuit is substantially 100 milliwatts. This amount of energy is insufficient to develop more than about 7 peak volts across the diode 18, 19 when a very strong signal modulated at 6000 cycles is encountered since to get any substantial response from a resonant circuit off its resonant frequency, a considerable amount of power is required to drive it. The 7 volts developed across the diode is 3 volts less than the minimum voltage required to develop any direct current voltage across R11 so that no output voltage whatsoever is developed in the diode circuit and the tone switch is not operated to render the director effective to lock the receiver on the 6000 cycle modulated carrier.

When a very strong undesired carrier is swept over, a large transient voltage is developed as the slope of the resonance curve of the receiver slides past the carrier frequency. This strong transient does, by shock excitation, cause the oscillation of circuits TC3, TC4 at their own resonant frequency, but due to the extremely limited driving power provided in the output circuit of tube VT7, only about 5 volts is generated across the circuit TC4 after amplification by VT8 which is, of course, insufficient to overcome the biasing voltage of diode 18, 19 so that no switch operating voltage is developed.

The sweep oscillator 14 and its associated filter circuit comprising R1 and C4 illustrated develops a substantially sine shaped voltage wave to effect the scanning action, but it will be understood that a source which generates a voltage wave of other desired shapes such as triangular, sawtooth, etc., may be used instead, as explained in more detail in the aforementioned application.

It has been noted after considerable experience with receivers of this type that as the frequency is raised we can attain such a frequency that the ordinary noises which prove so troublesome in ordinary reception, such as static, diathermy machines, sparking commutator motors and ignition noises, gradually die out, and at some vague point, probably below 150 megacycles, become extremely rare in a sharp receiver. There is left, of course, the thermal agitation noise in the circuits and the noise and shot effects in the tubes. This is a more or less regular hiss type of noise of quite a

definite and dependable character and is easily recognized by anyone skilled in the art.

Where space and weight are no consideration in designing a receiver of this type, we should probably always prefer a definite sweep voltage such as that produced by the 0.5 cycle oscillator shown in Figure 2, but experience has shown that if the switch SW2 be closed, the fluctuating noise voltages produced in the output of the audio stage VT7 by the amplification of the thermal agitation and shot effect current of the first stage is sufficient to sweep the control tube through its entire range quite rapidly and at random, but in a given period we find we cover the entire useful range of sweep in less than a second, although it is recognized that several pulses of the same polarity may follow each other rather than the smooth pulses of always alternate polarity which we obtain from the more disciplined action of the 0.5 cycle oscillator, which is, of course, omitted under this condition. The above condition obtains only when the receiver is of great sensitivity, i. e., so sensitive as to develop on peaks a voltage sufficient to fully control the control tube.

25 The tuning ranges of receivers of the type described are of two distinct classifications: first, for comparatively large tuning ranges that are to be covered, where operation may be expected on any one frequency throughout these large ranges; 30 and, second, where specific point-to-point service might be set up on an assigned frequency. In this latter case, no tuning range at all in the ordinarily accepted sense is required, but merely excursion around the assigned frequency to establish contact between transmitter and receiver at will. In this latter case probably much closer tolerances can also be expected with respect to the accuracy of the transmitter frequency, as it would probably be crystal controlled, and only 35 the receiver errors would remain. We thus have the two conditions, one a large tuning range and a small sweep range; the other, no tuning range at all, but a sweep range probably considerably less than 1%.

40 45 In a receiver designed for operation over a tuning range of from 100 to 200 megacycles the following circuit constants are found suitable.

$R_4=R_2=0.5$ megohms	$C_1=C_2=C_3=C_4=0.5$ mf
$R_3=R_4=0.2$ megohms	$C_5=C_6=100$ mmf.
$R_5=R_6=2.0$ megohms	
$R_7=10$ megohms	
$R_8=400-1500$ ohms	$R_{10}=25,000$ ohms
$R_9=0.5$ megohms	$R_{11}=125,000$ ohms

50 55 The general B+ supply is 250 volts. Vacuum tubes of the following types are found suitable for use with the circuits described:

VT1=type 6J7 pentode	
60 VT2=type 6H6 double diode	
VT3=type 955 acorn triode	
VT4=type 954 acorn pentode	
VT5, VT6=type 6N7 double triode	
VT7, VT8=type 6N7 double triode	

65 70 In using the receiver, the operator tunes the input circuit of the radio frequency amplifier 3 so that it will pass the carrier frequency or frequencies of the transmitter or transmitters with which it is desired to establish contact. In the illustrated embodiment this tuning is effected by manual adjustment of the permeability tuning means 4 which is uncontrolled in any known manner with the tuning means 29 of the oscillator. Since the frequency of oscillator VT3 is be-

ing cyclically varied through the action of the control tube VT4 whose reactance is in turn being cyclically varied by the sweep oscillator VT5, VT6, as soon as a carrier appears which forms a beat frequency with the oscillator frequency which lies within the frequency band passed by the intermediate frequency amplifier 6, an energizing voltage is applied through lead 23 to the control grid of the director driver tube VT1. If the received carrier is not modulated by the proper tone frequency, the tube VT1 is blocked in the manner above explained and no director voltage is built up in the circuits TC1, TC2, so that the receiver is not locked on the carrier, but the scanning action is continued under the control of the sweep oscillator 14. Upon receiving a desired carrier which is modulated with the tone frequency to which the tone filter circuits TC3, TC4 are resonant, a tone switch operating voltage is developed across the diode resistor R11 which is sufficient to substantially block the tube VT10. This action causes the voltage of screen 25 to rise very substantially, so that the plate current of VT1 energizes the director VT2, and a minimum director voltage of ± 20 volts is developed and through line 22 is applied to the control grid of the control tube VT4. This high voltage overpowers the control voltage of ± 3 volts developed by the sweep oscillator and serves to maintain the reactance of the control tube at a constant value, thereby maintaining the oscillator frequency at a constant value which heterodynes with the carrier frequency to produce the proper beat frequency which lies within the band of frequencies passed by the intermediate frequency amplifier 6. The receiver remains locked on the carrier as long as the tone modulated carrier is received. If the carrier disappears, no voltage is supplied through line 23 to energize the director with the result that no director voltage is developed and the receiver resumes the scanning condition under the control of the sweep oscillator 14. If the carrier continues to be received but the tone modulation disappears, no currents are available of the tone modulation frequency in the output circuit of tube VT1, so that no switch operating voltage is developed by the tone filter. This causes the tube VT10 to draw a heavy plate current, and the voltage of screen 25 to drop low enough to block the director driver tube VT1. Since no director voltage is now developed or applied to the control grid of the control tube, the sweep oscillator resumes control of the control tube and the scanning operation is resumed.

The ability of this receiver to respond only to a carrier designated by a given tone allows the frequency of the transmitted carrier to be shifted at will over rather large ranges of frequencies, and, since the receiver is locked on the carrier, it would faithfully follow such changes if they are continuous. If the carrier frequency were varied in a smooth and continuous manner, some difficulty would ensue if it happened to pass over an undesired carrier, so it is preferred to cause the carrier frequency to vary in a discontinuous manner. The receiver, in reestablishing contact after such a discontinuity in frequency, has the ability of passing over an undesired carrier, which it might encounter in passing to the new carrier frequency, without any slowing down in its scanning action. It is accordingly one of the purposes of this invention to provide a scanning receiver in which the scanning and identifying action is so rapid that a continuous communica-

tion may be kept up on the several separate carrier frequencies alternately without any noticeable lapse. One field of use for a receiver of this type is in the establishing of communication where secrecy is desired.

Where a receiver of this type is to be used in point-to-point communication where there is no possibility that the carrier wave will seriously weaken once contact has been established, it is perfectly feasible to operate the receiver in the "tone lock, carrier hold" condition. In this condition the tone is impressed on the carrier only for a second or so to be sure the receiver has had time to lock on the designated carrier, and the tone is then removed leaving the receiver locked on the carrier. Means for doing that include the connection 35 and the switch SW1. Upon closure of this switch the receiver is placed in the "tone lock, carrier hold" condition, since any negative voltage developed across R1 will be applied to the grid of VT10, the switch tube.

Assuming a receiver to have scanned its usual portion of the spectrum, and encountered a carrier having a proper tone to which TC3 and TC4 are tuned, the necessary switch operating voltage will appear across R11 and be applied to VT10. While the receiver is scanning, of course, VT1 is blocked and no voltage can appear across R1. However, once VT10 switch tube has been blocked, VT1 in turn is unblocked and a negative voltage builds up across R1 due to the carrier wave. This negative voltage is immediately applied to the grid of VT10 through the connection 35 and is of sufficient amplitude to maintain VT10 in a fully blocked condition. If the tone is now removed from the carrier, the voltage from R1 will hold the system in operative condition until such time as the carrier wave disappears. It is obvious that once the carrier disappears, the receiver resumes the scanning condition and will again lock only when a carrier identified by the proper tone is encountered. The term "scanning receiver" as used in the claims designates a radio receiver which automatically explores a plurality of communication channels in succession lying between two definite frequencies in the spectrum. The term "inertialess" as used in the claims designates a control means having no moving mechanical parts and hence free of mechanical inertia.

While the receiver shown in Figs. 1 and 2 and above described is a single superheterodyne, the apparatus in which the invention was developed was a double detection type superheterodyne with a first intermediate frequency of 17.5 megacycles and a final intermediate frequency of 0.46 megacycle.

I have described what I believe to be the best embodiments of my invention. I do not wish, however, to be confined to the embodiments shown, but what I desire to cover by Letters Patent is set forth in the appended claims.

I claim:

1. A radio receiver adapted to receive a tone modulated carrier wave and comprising a circuit tunable over a range of frequencies but normally untuned to the carrier frequency, automatic means for continuously tuning said circuit over the frequency range, and automatic means responsive to the tone modulations of a single continuous impulse of the tone modulated carrier for rapidly arresting the action of said tuning means and for maintaining said circuit tuned to a desired frequency within said range of frequencies.

2. A radio receiver arranged to rapidly and automatically scan a plurality of adjacent communication channels, the carrier wave of one channel being modulated at different times at different predetermined tone frequencies, said receiver comprising means for detecting the modulation frequency, a pair of tone filters connected to said detecting means and each responsive to one of said tone frequencies, and means connected to both of said tone filters and operative upon the reception of a single continuous pulse of a carrier modulated by either of the tone frequencies to rapidly arrest the scanning action of the receiver and lock it on said tone modulated carrier.

3. A radio receiver for receiving a tone modulated carrier wave comprising, in combination, a tunable circuit, means for automatically and continuously tuning said circuit over a range of frequencies as wide as a plurality of communication channels, a diode having an input circuit, a tuning control device connected to the diode, and means connected to the diode for causing said tuning control device to rapidly arrest the continuous tuning of said circuit and to maintain the circuit resonant at a desired frequency in response to the impression of voltages of the tone modulation frequency of the carrier on the input circuit of the diode.

4. In combination with a radio receiver of the superheterodyne type for receiving a tone modulated carrier wave and having an oscillator and a second detector, a diode having an input circuit coupled to the output of said second detector, a tuning control device connected to said diode and to the input of said detector and including a reactance control tube connected to said oscillator, and means connected to the diode for causing said tuning control device to maintain the frequency of the oscillations generated by the oscillator at a desired value in response to the impression of voltage of the tone modulation frequency on the input circuit of the diode by the second detector.

5. A scanning receiver having means for automatically tuning it over a plurality of communication channels and means for automatically arresting the scanning action thereof and for rendering said receiver continuously responsive to a tone and signal modulated carrier wave, said means comprising a driver tube having an output circuit of limited power output and comprising a device resonant to the tone modulation frequency of the carrier, and a detecting device coupled to said output circuit and having the property of being substantially responsive only to voltages generated in the responsive device which are greater than a predetermined value.

6. A radio receiver for a transmitted carrier wave having tone and signal modulations, said receiver being tunable over a range of frequencies including a plurality of carrier frequency channels, means free of mechanical inertia for cyclically and automatically tuning said receiver over the frequency range, control means responsive to the reception of the carrier frequency, and means responsive to the tone modulations of the carrier for rendering said control means effective to maintain the receiver tuned to a desired frequency.

7. In combination with a radio receiver of the superheterodyne type for receiving tone modulated carrier waves of different frequencies within a band of frequencies, said receiver comprising a first detector and an oscillator, means for

automatically and cyclically varying the frequency of the currents generated by said oscillator throughout a range substantially equal to said band, means for detecting the modulations of the carrier, and means coupled to said detecting means and responsive to the tone modulations of a desired carrier for causing the frequency of the currents generated by the oscillator to remain at a desired value.

10. 8. In combination with a radio receiver of the superheterodyne type for receiving tone modulated carrier waves and comprising an intermediate frequency amplifier, a detecting device connected to the intermediate frequency amplifier and adapted to detect the carrier modulations and an electron discharge tube oscillator having a grid circuit and a plate circuit tunable over a range of frequencies, a reactance generating control tube having a plate circuit and a grid circuit, means connecting the plate circuits of said tubes in parallel, means for generating a fluctuating voltage coupled to the grid circuit of said control tube, a frequency responsive director device continuously connected to a grid of said control tube and adapted to control the transconductance of said tube, a switching device operative to selectively connect said director device to the intermediate frequency amplifier, and means connected to said detecting device and including a filter circuit responsive to the tone modulations of a desired carrier wave for operating said switching device to thereby cause the director device to be energized by the amplified intermediate frequency currents.

35 9. A radio receiver adapted to receive tone modulated signal currents of different carrier frequency channels within a band of frequencies higher than 20 megacycles and comprising, in combination, means free of mechanical inertia operative to automatically and cyclically tune said receiver over the frequency band, and means responsive to the reception of a tone modulated carrier having a frequency within said band for rendering said means ineffective to continue the tuning of the receiver over said band and to automatically permit the cyclic tuning of the receiver by the tuning means again, in response to the disappearance of the tone modulations of the carrier.

50 10. A radio receiving system comprising, in combination, a radio receiver adapted to receive tone modulated signal currents, said receiver having a high order of sensitivity and being tunable over a range of frequencies higher than 20 megacycles including a plurality of communication channels, an amplifier coupled to the output of said receiver and having a fluctuating noise current component when the receiver is untuned to a carrier frequency within said range, means energized by the noise component of the amplifier for causing the random tuning of the receiver over said range of frequencies and means responsive to the tone modulation of a carrier for stopping the random tuning of the receiver and for locking it on such tone modulated carrier.

55 11. A radio receiving system for tone and signal modulated carrier waves, said system comprising, in combination, an input circuit, a communication channel, a detector device connected to said input circuit for detecting the tone modulations of the carrier, automatic means for cyclically varying the frequency of the signaling energy impressed on said communication channel by the input circuit at a substantially steady

rate in one direction and at a more abrupt rate in the opposite direction, and means connected to the output of said detecting device and responsive to the tone modulations of a carrier for overcoming the effect of said automatic frequency varying means and for maintaining the frequency of the signaling energy impressed on the communication channel at a desired value.

12. A radio receiver for a carrier having tone and signal modulations, said receiver comprising, in combination, an input circuit including an amplifier, a communication channel, automatic means for automatically varying at a rapid rate the frequency of the signaling energy impressed on said communication channel by the input circuit, an automatic volume control device arranged to vary the amplification of said amplifier inversely as the strength of a received carrier and having a time constant of such value that the amplification of the amplifier is not substantially reduced upon the reception of another carrier passed over at the rapid rate and unmodulated by the tone modulations, and means responsive to the tone modulations for maintaining the frequency of the signaling energy impressed on the communication channel at a desired value.

13. A receiver adapted for the continuous reception of a signal transmitted in sequence on at least two different carrier frequencies each of which is modulated by a predetermined tone, 5 said receiver comprising a tunable input portion, means for tuning said input portion to one of the carrier frequencies, means for automatically tuning said input portion to the other carrier frequency and for maintaining said input portion tuned to said other frequency, and means for rendering said last named means ineffective to maintain said tunable input portion tuned to a carrier frequency unmodulated by the predetermined tone.

14. A scanning receiver for the reception of tone modulated carrier waves of different frequencies, the receiver being normally untuned to a desired carrier comprising, in combination, means responsive to a predetermined tone for locking the receiver on a carrier modulated by said predetermined tone, and means responsive to currents of the carrier frequency for maintaining the receiver locked on the carrier upon the disappearance of the tone modulations.
